UNITED STATES PATENT OFFICE.

JOHN HENRY KLENCK AND MAX WILLIAM LARSEN, OF WARREN, PENNSYLVANIA.

LOCK FOR BLOCK-SIGNAL-CONTROLLING LEVERS.

1,364,285.

Specification of Letters Patent.

Patented Jan. 4, 1921.

Application filed December 27, 1919. Serial No. 347,780.

To all whom it may concern:

Be it known that we, JOHN HENRY KLENCK and MAX WILLIAM LARSEN, citizens of the United States, residing at Warren, 5 in the county of Warren and State of Pennsylvania, have invented certain new and useful Improvements in Locks for Block-Signal-Controlling Levers, of which the following is a specification.

10 This invention relates to an automatic safety locking means for levers; and the invention is especially adapted to semaphore control levers such as are used in a block signal system.

15 The control levers of the above mentioned class are usually arranged in sets and located in a tower and the operator moves his levers to change the indicating semaphore in accordance with track conditions and instructions received from the train dispatcher.

20 Each lever operates on a quadrant and is provided with latching means engaging the quadrant to maintain the lever in certain set positions, but said latching means is controlled by the lever operator from the handle of the lever and hence the movement of the lever is subject to human error to a considerable extent and therefore the lever may 25 be moved past a selected point, the latch may not seat or, in excitement, the operator may not be aware of which position he is placing the lever in.

25 In block signal control levers the quadrant is divided into three lever positions, namely "stop or normal position" in which the track semaphore indicates to the engineers of the train that the block is occupied and must not be entered; "permissive or proceed with caution position" indicating that the preceding train has not left the block and close watch is to be kept ahead for the rear of the preceding train; the third position of the lever is that of "clear or open" 30 block in which case the semaphore indicates to the engineer on the train that the block his train is about to enter is entirely clear. It is obvious that if the operator of the lever misses placing the lever in a proper position 35 to indicate the condition of the track ahead disastrous results may occur and, in fact, most often do. A typical example of this would be if the operator should move the lever from "stop position" through "permissive" position to "clear block" position and immediately return it to "permissive posi-

tion" where he had originally intended to engage the lever latch; suppose just at the moment the semaphore turned up "clear block" the engineer on the train had 60 his gaze directed on it and seeing all was clear immediately looked away and then the semaphore registered "permissive," the chances are a serious rear end collision with consequent loss of life and property would 65 result.

It is the prime object of this invention to eliminate the above mentioned "human element of error" by providing means to positively warn the operator what position he is 70 moving the lever into.

A further object is to provide a lock which may be manually set in a safety position to prevent movement of the lever from a set position when left for any length of time as 75 when the operator leaves the tower.

In the drawings:

Figure 1 is a side elevation of a control lever set in the normal or stop position;

Fig. 2 is a similar view of the control lever 80 set in the permissive or caution position;

Fig. 3 is a similar view showing the lever in the "clear block" position;

Fig. 4 is a similar view showing the lever manually locked in the normal or stop position;

Fig. 5 is a similar view of the lever manually locked in the "clear or open block" position;

Fig. 6 is a view, in perspective, of the shifting jaw, and

Fig. 7 is a perspective of the control lever dog.

The lever 1 moving on a quadrant 2 to shift the semaphore and lever co-operating 95 element 3 by the cam action of the members 4 on the flange 5 of the element 3 are all standard parts of the usual lever set; and the lever 1 carries a latch 7 having a connecting link 8 carried in lugs 9 and actuated 100 downwardly into engagement with notches A, B and C of the quadrant 2 by spring 10, said link 8 being movable by a finger piece (not shown) on the upper end of the lever 1 to disengage the latch 7, the foregoing 105 latch mechanism also being standard in the usual lever set. It is in the operation of this latch member 7 that the element of "human error" plays its part for the latch mechanism is under the control of the operator 110 who may easily slip the lever 1 unwittingly past a selected position.

In order to prevent such slips the lever 1 is provided, on its side with a dog 11 secured in place by bolts 12. The dog 11 extends downwardly of the lever 1 and is offset as shown at 13 so that the end 14 thereof overlaps the side of the quadrant 2; the one side 15 of said dog presents a straight abutment whereas the lower corner of the other side carries a laterally extending tooth 16 having a curved upper face 17 merging into the side 18 of said dog. The dog 11 is perforated as at 19 and 20 to receive the shanks of bolts 12.

Two studs 21 and 22 alining in a horizontal plane are mounted on the side of the quadrant 2 and carry a shifting jaw 23 secured against removal from said studs 21 and 22 by washers 24 and nuts 25 on said studs. The shifting jaw 23 is shown clearly in Fig. 6, and is merely a flat piece of metal having a curved edge 24 centrally interrupted by a cut-out 25 having an under cut 26 for engagement by the tooth 16 of the dog 11. Adjacent the ends of the shifting jaw 23 are slots 27 and 28 inclined ways 29 and 30, respectively, of which diverge toward the bottom of the jaw and the former of which terminates in an offset laterally directed approximately circular cut-out 31 having a projecting point of intersection 32, similarly the inclined way 30 terminates in an enlarged cut-out 33 connected with the way 31 by a downwardly inclined surface 34, the intersecting point 35 of which extends below the uppermost portion of the cut-out 33. The two slots 27 and 28 are not of uniform shape and the cut-outs 31 and 33 extend in opposite directions. The slots 27 and 28 are so shaped, as above described, that the shifting jaw 23 may assume any one of the positions shown in Figs. 1 to 5 inclusive.

In Figs. 1 to 5 the various positions of the lever 1 are indicated on the latch notches A, B and C for receiving the latch member 7, as follows:

A—stop or normal position.

B—permissive or proceed with caution position.

C—clear or open block position.

The normal position of the lever 1 is in notch A indicating "stop" and the normal position of the shifting jaw 23 is as shown in Fig. 1 with the stud 22 in the cut-out 33 where it is retained by the intersecting point 35 and the stud 21 in the upper end of the inclined way 29 of the slot 27 and the undercut 26 in the path of the tooth 16 of dog 11; when the parts are in the positions above set forth suppose the operator receives a message from the train despatcher indicating "clear block" which requires him to move the lever 1 to notch C, he raises the detent latch member 7 and moves the lever 1 toward notch C but at notch B the tooth 16 of dog 11 engages under the cut-out 26 and by

reason of the coöperating curved adjacent surfaces of the tooth 16 and cut-out 26 the shifting jaw is slightly raised to disengage intersecting point 35 from stud 22 and on continued movement of the lever the parts assume the position shown in Fig. 2 with the shifting jaw 23 in such a position on the stud 22 that if the tooth 16 is disengaged the forward end of said shifting jaw will drop to assume the position shown in Fig. 3; therefore in order to accomplish further movement of lever 1 the operator moves lever 1 slightly back and disengages tooth 16 but by the stopping of the lever automatically he has been warned that he is passing through the "permissive or caution" position; as soon as the shifting jaw moves to the position shown in Fig. 3 the operator may move the lever to the "clear" position as also shown in Fig. 3. Now, the parts being in the position shown in Fig. 3 the next movement of the lever is to be back through notch B to notch A or "stop" position, and in accomplishing this move by operating the lever 1 in the direction of the dotted arrow in Fig. 3 the straight abutting edge 15 engages point 36 of the shifting jaw 23 moving the same until it drops by gravity to the position shown in Fig. 1; the operator may then, if desired, lock the lever 1 in this position by manually raising the shifting jaw 23 to the position shown in Fig. 4, so that the end 37 stands in the way of dog 11 and prevents movement of lever 1; similarly, if it is desired to lock lever 1 in the "clear" position shown in Figs. 3 and 5, the shifting jaw 23 is manually moved to the position shown in Fig. 5 and the end 38 stands in the way of dog 11 and prevents movement of the lever until shifting jaw 23 is manually moved to the position shown in Fig. 3. In any event, it is seen that in moving the lever from "stop or normal" position to "clear or open block position" full throw of the lever cannot be accomplished without stopping momentarily in "permissive or proceed with caution" position which positively and automatically eliminates the human element of error.

Having thus described the invention, what is claimed as new is:

1. In combination, a quadrant, a lever movable on said quadrant to several positions, safety lever locking means automatically engaging to lock said lever in one position and manually operable to lock said lever in other positions.

2. In combination, a quadrant, a lever movable on said quadrant to several positions, and safety lever locking means automatically engaging to lock said lever in one position exclusive of any other indicated positions on the quadrant and manually operable to lock said lever in other positions.

3. In combination, a quadrant, a lever

movable thereon to several latched positions, and lever moved means causing said lever to automatically hesitate on movement through one of said latched positions to 5 warn the operator of movement through such latched position.

4. In combination, a quadrant, a lever movable thereon to several latched positions, and lever moved means causing said lever to 10 positively hesitate on movement through one of said several positions to warn the operator of movement through such latched position.

5. In combination, a quadrant having several notch positions, a lever movable on said quadrant to said positions, manually operable latch means for stopping said lever in any selected notch position, and lever moved 15 operable safety lock means for arresting 20 movement of said lever through a notch position.

6. In combination with a quadrant, a lever, latch means for retaining said lever in set positions, a dog carried by said lever and 25 cooperating with means on said quadrant to

automatically arrest movement of said lever at one set position.

7. In combination with a quadrant, a lever, latch means for retaining said lever in set positions, a dog carried by said lever, 30 and a coöperating automatically shiftable jaw for shifting engagement by said dog to move said jaw into position to engage said dog to stop said lever.

8. In combination with a quadrant, a lever, latch means for retaining said lever in any set position, a dog carried by said lever and having a tooth, a tilting jaw mounted on studs carried by said quadrant and having 35 a cut-out provided with a projection for 40 engagement with said tooth only on movement of said lever to a selected position, and releasable by a slight reverse movement of 45 said lever to permit gravitation of said jaw to a different position.

In testimony whereof we affix our signatures.

JOHN HENRY KLENCK. [L.S.]

MAX WILLIAM LARSEN.
